OTHER PUBLICATIONS

With its bold triangular shape able to adapt to various environments and reach tight corners, this low-noise robotic cleaner by Ceragem not only vacuums and mops but also sanitizes the surfaces it cleans—Global Design News (Year: 2022).*

Primary Examiner — Patricia A Palasik

(57) **CLAIM**

The ornamental design for a robotic vacuum cleaner as shown and described.

DESCRIPTION

1. Robotic vacuum cleaner

1.1 : Perspective

1.2 : Front

1.3 : Back

1.4 : Top

1.5 : Bottom

1.6 : Left

1.7 : Right

The design is a robotic vacuum cleaner that autonomously navigates the desired cleaning area without user intervention.
